N. Y., a corporation of New York

Application August 4, 1948, Serial No. 42,426

5 Claims. (Cl. 202—151)

1 This invention relates to the design and construction of the heating walls of a vertically flued coke oven battery and more particularly to the structure of the heating walls of underjet vertically flued coke oven batteries.

To obtain more uniform heating of the coking chamber walls and thus produce a more uniform rate of coking with consequent improvement in the quality of the coke, it has been suggested to provide the vertical flues in each heating wall with low-burner nozzles alternating with high-burner nozzles. Heretofore the high-burner nozzles have invariably been of the same height and this irrespective of the height of the coking chambers. In some cases this has resulted in overheating of the gas collecting space at the top of each coking chamber with consequent cracking of by-products in the coke oven gas passing through this space into the collector main and loss of valuable oils. It has also been suggested to employ burner nozzles having removable tips which can be replaced by a nozzle tip of different height through the roof of the battery and thus control the effective height of the nozzle in each flue. As a practical matter, however, once an oven battery is placed in operation it is a difficult, arduous and time-consuming task to effect, during operation, removal and replacement of one or more burner tips to position the burner nozzles in the flues at the desired height for optimum heating. In this country, at least, all oven batteries built involving high and low burner nozzles in the flues have nozzle tips permanently bonded to the burner nozzle brickwork because removable and replaceable tip-type burner nozzles have been found unsatisfactory for many reasons, including (1) they are more costly, (2) are more likely to break and crack, and (3) it is seldom, if ever, that a coke oven operator will undertake to replace one or more burner tips in a heating wall of a coke oven battery with burner tips of different heights in view of the difficulty in so doing once the oven battery is placed in operation.

Among the objects of this invention is to provide a vertical flue heating wall structure in which the burner nozzles are arranged at a level to provide for more uniform heating of the charge and to avoid overheating the gas collecting space at the top of the coking chamber. Other objects and advantages of this invention will be apparent from the following detailed description thereof:

I have found that by arranging the burner nozzles so that in the vertical flues of each heat-

2 ing wall a low-burner nozzle alternates with a high-burner nozzle, the low-burner nozzles being located at the base of the flues or having a height from the base of the flues not exceeding .5" per foot of vertical flue length, the high-burner nozzles in all flues except the group of flues at the coke side of the battery having a height from the base of the flue of from 2" to 2.75" per foot of flue length and the height of the high-burner nozzles of the group of flues on the coke side of the battery gradually decreasing in a direction towards the coke side of the battery at a rate of from 15% to 50% per unit decrease, uniform heating takes place with elimination of excessively hot oven tops avoiding cracking of valuable by-products. This arrangement of the burner nozzles, it has been found, properly takes into account the various factors affecting heating of the charge, such as oven taper and the fact that greater heat radiation losses take place at the sides of the battery than at the remaining portions of the heating walls flanking the coking chambers so that more fuel gas must be fed to the flues on the coke side of the battery. It also takes into account variations in the heights of the coking chambers of different batteries since the height of the burner nozzles in the heating wall structure of this invention is determined by the length of the vertical flues which in turn is determined by the height of the coking chambers. Hence, this invention results in a material improvement in the heating of the coking chamber charges both from the standpoint of effecting uniform coking and avoiding overheating of the gas collecting space at the top of each coking chamber.

In the preferred embodiment illustrated on the drawings, the invention is shown incorporated in an underjet coke oven battery and the description which follows will be confined chiefly to the present illustrated embodiment of the invention. It will be understood, however, that the novel features and improvements are not limited to this embodiment of the invention. The invention includes, for example, coke oven batteries of the twin-flue and cross-over type in which the heating flues of one heating wall are connected with the heating flues of another heating wall. Hence, the scope of this invention is not confined to the embodiment herein described.

50 In the accompanying drawings forming a part of this specification and showing, for purposes of exemplification, a preferred embodiment of the invention but without limiting the claimed invention to this embodiment,

Figure 1 is a vertical section through a heating

wall of a coke oven battery embodying the present invention; and

Figure 2 is a composite fragmentary vertical section taken lengthwise of the battery, the left hand portion being taken in a plane passing through a charging opening and the right hand portion taken in a plane passing through the roof of the coking chamber in a locality between the charging openings.

Referring to the drawings, the coke oven battery comprises a deck or oven base 10 which extends the full length and width of the battery and supports the battery brickwork. The deck 10 is ordinarily formed of reinforced concrete and may be a single slab, although preferably it is divided into a plurality of longitudinal sections separated by expansion joints, as is well known. This deck 10 is supported by a multiplicity of columns 11 which may be of reinforced concrete. These columns are disposed longitudinally of the battery and also crosswise of the battery. Concrete walls 12 and 13 are disposed at the sides of the battery producing with the deck an enclosed basement space 14. Conventional pinion walls 15 (Figure 2) are provided at the ends of the battery for additionally supporting deck member 10 and for retaining in place the brickwork hereinafter described supported on the deck member 10.

Supported on deck 10 is a plurality of coking chambers 16 and a plurality of crosswise-extending intermediate heating walls 17. Each coking chamber in horizontal cross-section is of tapered shape as is conventional, the wide end of the coking chamber being on the coke side of the battery, i. e., the side at which the coke is discharged from the coking chambers, and the narrow end on the pusher side. Coal to be coked is charged into the coking chambers through conventional charging openings 18 leading from the top of the battery to the coking chambers, which openings are equipped with the usual removable covers.

In the embodiment of the invention shown on the drawings each heating wall involves a row of vertical flues consisting of two exterior and two interior groups of flues, the exterior groups operating concurrently for inflow while the interior groups operate concurrently for outflow. Upon reversal, the interior groups of flues operate concurrently for inflow while the exterior groups operate concurrently for outflow. Thus a concurrently operable group of flues 19-26, inclusive, on the pusher side of the battery is connected by horizontal flue 27 with the tops of an interior group of flues 28-35, inclusive. On the coke side of the battery an exterior group of flues 36-41, inclusive, is connected by horizontal flue 42 with an interior group of flues 43-49, inclusive.

The flow through each flue may be regulated by a slide brick or damper brick 50 to vary the extent of the passage connecting the vertical flues with the horizontal flues through access flues 51 which extend from the horizontal flues to the top of the battery. The tops of the vertical flues are disposed at a level below the top of the normal level of the charge introduced into the coking chamber, which latter level is indicated by the reference character 52 in Figure 2 and defines the base of the gas collecting space 53 at the top of each coking chamber. The tops of the vertical flues desirably are spaced from 15" to 30" below the normal charge level 52. By the tops of the vertical flues is meant the point 54 where the vertical flues join the horizontal flues 27, 42. Thus the length of each vertical flue

is the distance from the base of the flue to point 54 where the flue joins the horizontal flue.

The base of each vertical flue, it will be noted, is at the same level as the base of the coking chambers 16. Further, the bases of all vertical flues in each heating wall are at the same level. Alternate vertical flues of each heating wall each have at the base thereof a low-burner nozzle 55. This burner nozzle may have its tip flush with the base of the vertical flue, may even be somewhat below the level of the base of the vertical flue, or may extend to a height not exceeding .5" per foot of vertical flue length. Preferably each low-burner nozzle 55 is of a height of from .35" to .5" per foot of flue length.

The remaining flues in the group of flues 19-26, inclusive, namely flues 20, 22, 24 and 26, are each provided with a high-burner nozzle 56 of a height of from 2" to 2.75" per foot of vertical flue length.

Flues 29, 31, 33, 35, 48, 46 and 44 are each provided with a high-burner nozzle of the same height as nozzle 56. In the group of flues 36-41, inclusive, on the coke side of the battery the high-burner nozzles are of gradually decreasing height in a direction toward the coke side of the battery.

Thus the high-burner nozzle 57 in flue 41 is of the same height as the high-burner nozzle 56. The high-burner nozzle 58 in flue 39 is of a height within the range of from 1.6" to 2.2" per foot of

flue length and the high-burner nozzle 59 in flue 37 is of a height within the range of from 1.2" to 1.8" per foot of flue length; the height of the high-burner nozzles in the flues 41, 39 and 37 decreases from one high-burner nozzle to the next by at least 15%, preferably by an amount within the range of from 15% to 50%. Thus, for example, for a vertical flue oven having coking chambers 12' high and vertical flues 8' 10 $\frac{1}{2}$ " high, nozzles 56 and 57 may be 22" high, nozzle 58, 18" high and nozzle 59, 12" high. By the height of burner nozzle is meant the distance the burner nozzle extends above the base of the flue. Each burner nozzle is built up of brickwork permanently bonded to the heating wall brickwork.

Each burner nozzle receives fuel gas, such as coke oven gas or other rich fuel gas, through an individual uprising channel 60 extending through deck 10 and connected at its lower end with one of a pair of crosswise extending gas distributing mains 61 disposed in the basement space 14 near the top thereof. One such pair of mains is provided for each heating wall. These crosswise extending mains 61 are provided with individual uprising channels 62; one of each pair of mains 61 is provided with such channels communicating only with the exterior groups of flues in the heating wall thereabove and the other main of the pair with such channels communicating only with the interior groups of flues in the heating wall thereabove. Each uprising channel 62 at the point where it is connected with main 61 is provided with a flow regulator (not shown) controlling the flow of gas supplied to the flue. This flow regulator preferably is of the type described and claimed in Patent 2,199,961 of May 7, 1940. These regulating devices require attention and occasional adjustment by an attendant working in basement space 14.

Each main 61 communicates with a rich gas supply main 63 connected therewith by means of piping 64. Main 63 is suitably insulated against loss of heat. Piping 64 is provided with a three-way valve 65 and a shut-off valve 66 which is normally open. Leading into the three-way valve 65 is a pipe 67 which communicates with

a decarbonizing air main 68 suitably supported in the basement space 14. Operation of the three-way valve 65 by the usual automatic reversal mechanism functions to place the main 68 into communication with the main 63 serving to supply coke oven gas to the inflow flues and to place the decarbonizing air main 64 into communication with the mains 61 to which coke oven gas is not being supplied. Upon reversal of operation the three-way valve is operated to place decarbonizing air main in communication with the cross mains 61 to which previously fuel gas had been supplied in accordance with customary procedure of supplying fuel gas and decarbonizing air to the gas distribution systems of coke oven batteries.

The regenerator structure of the battery involves supporting pillar walls 69 disposed directly below the heating walls 17 and rows of crosswise extending regenerators 70 separated by the pillar walls, each row of regenerators comprising two exterior regenerators and an interior regenerator. The exterior regenerators of each row of regenerators are connected by ports 71 with the exterior groups of flues on opposite sides of the coking chamber 16 thereabove. The interior regenerators of each row are likewise connected by ports 71 with the interior groups of flues on opposite sides of the coking chamber directly above it.

When the battery is operated as a combination oven, alternate exterior regenerators of each exterior row of regenerators lengthwise of the battery during one period of operation operate for inflow of preheated air, and the remaining exterior regenerators of each exterior row lengthwise of the battery operate for inflow of lean fuel gas such as blast furnace or producer gas into the communicably connected outer groups of flues 19 to 26 and 36 to 41, both inclusive, located on opposite sides of the coking chamber thereabove, while the products of combustion pass downwardly through the inner groups of flues 28 to 35 and 43 to 49 on opposite sides of each coking chamber into the inner regenerators. Upon reversal the inner regenerator of each crosswise extending row of regenerators and the flues communicating therewith operate for inflow while products of combustion pass downwardly through the outer groups of flues into the outer regenerators; alternate regenerators of the inner regenerator row lengthwise of the battery operate for inflow of air and the remaining regenerators of this row operate for inflow of lean gas. Thus, all of the regenerators in alignment longitudinally of the battery operate simultaneously for flow in the same direction. When operating with rich gas supplied through channels 60 to the burner nozzles in the flues, all of the inflow regenerators operate for inflow of air to support combustion of the gas fed to the flues.

Located at the pusher side of the battery is an air channel or passageway 72 running the full length of the battery to which air may be supplied through one or both ends thereof. If desired, a fan or blower (not shown) may be disposed at one end of the air channel 72 with its outlet arranged to blow the air at any desired pressure, say at about 5 mm. of water above atmospheric, into the channel 72. The air admitted to the channel may be passed through a filter cloth or other screen so that clean air of predetermined humidity is admitted to the channel and flows through openings 73 into the basement space 14 and from this space into the regenerators. Operating in this manner air of

constant oxygen content is admitted to the regenerators throughout the year minimizing the necessity of changing adjustments of the regulating devices with seasonal changes in atmospheric conditions. Furthermore, comfortable conditions for the attendant are maintained in the basement space 14 at all times.

A chimney flue 74 is located on the coke side of the battery and runs the full length thereof. Located at the same side of the battery as the chimney flue are reversing valves 75 which may take various forms and which collectively provide for the discharge of the products of combustion from the regenerators through the sole channels 76, 77 (Figure 2), into chimney flue 74 and for the supply of air and lean fuel gas to the regenerators. Air is supplied to the air inflow regenerators through passageways 78 communicably connecting the basement space 14 with the sole channels 76, 77. Lean gas is supplied to the gas inflow regenerators from a lean gas main (not shown) communicating with these regenerators through passageways 78. In the structure shown on Figure 1 valves 78' control the flow of air from the basement space 14 through the passageways 78 into sole channels 76 or 77 of the air inflow regenerators; like valves control the flow of lean gas into the gas inflow regenerators. A valve 79 is provided for controlling the flow of products of combustion from each sole channel 76, 77 of each outflow regenerator into the chimney flue 74. A butterfly valve 80 is positioned in a passageway 81 connecting each sole channel 76, 77 with the chimney flue 74, which butterfly valve may be suitably positioned by the operator to obtain the desired stack draft, causing flow of the products of combustion into the chimney flue 74.

It will be understood valves similar to 78' and 79 are provided for the sole channels communicating with each of the regenerators of each row of regenerators, which valves control the flow of air into the air inflow regenerators from the basement space 14, the flow of lean gas into the gas inflow regenerators and the flow of products of combustion from the outflow regenerators into the chimney flue 74. Thus, when the valves 78' controlling the flow of air and lean gas into the interior regenerators along the length of the battery are closed, the corresponding valves controlling the flow of air and lean gas into the exterior regenerators are open. Likewise, when the valves 79 controlling the flow of products of combustion from the interior regenerators along the length of the battery into the chimney flue 74 are open, the corresponding valves 79 in the passageways connecting the sole channels of the exterior regenerators with the chimney flue 74 are closed. Each passageway connecting the

basement space with the sole channel may be provided with a port 82 which may be throttled by removable and replaceable finger bars.

It will be understood the above described regenerator, chimney flue and air duct structure represent one desirable arrangement and that other arrangements of regenerators, air and gas supply means therefor and chimney flues may be used.

By positioning the low-burners, as hereinabove described, in alternate flues of each heating wall, efficient heating of the charge at the base of the coking chamber is accomplished. The position of the high-burners hereinabove disclosed, it has been found, results in uniform heating of the charge and this without causing spillage of un-

burned gas into the horizontal connecting flues which would result in combustion taking place in these flues with consequent overheating of the gas-collecting space. By having the high-burner nozzles in the group of flues on the coke side of the battery of decreasing height, the necessary increased amount of gas required to heat the larger charge in the wider end of the coking chamber disposed at the coke side of the battery can be supplied and this without causing spillage of unburned gas into the horizontal connecting flue, as has been the case in prior coke oven constructions involving high- and low-burner nozzles.

The drawings illustrate the invention applied to a battery equipped with heating walls arranged in two exterior and two interior groups. It will be evident that the invention includes batteries involving other vertical flue arrangements, such for example as the twin vertical flue arrangement disclosed in my Patent No. 2,407,356 granted September 10, 1946, and batteries in which the vertical flues of one heating wall are interconnected with those of another heating wall. This invention is applicable to combination vertical flue oven batteries adapted to be heated by a rich gas such as coke oven gas and/or an extraneously derived gas such as blast furnace gas, as well as batteries designed to be heated by rich gas exclusively. Further, as above indicated, the invention may be incorporated in batteries having different regenerators and waste heat flue arrangements than that disclosed.

Since certain changes may be made without departing from the scope of the invention, it is intended that the above description shall be interpreted as illustrative and not in a limiting sense.

What is claimed is:

1. In a coke oven battery having heating walls and coking chambers arranged in side by side alternate relationship, vertical heating flues in each heating wall and alternate high- and low-burner nozzles in the bases of the vertical heating flues of each heating wall, the high-burner nozzles, except those in the vertical flues on the coke side of the battery, being of substantially the same height and having a height within the range of from 2." to 2.75" per foot of heating flue length and the high-burner nozzles in the said flues on the coke side of the battery decreasing in height in a direction towards the coke side of the battery, the decrease in height of one high-burner nozzle to the next being at least 15% and the height of the highest high-burner nozzle in the said flues on the coke side of the battery being within the range of from 2." to 2.75" per foot of heating flue length.

2. In a coke oven battery having heating walls and coking chambers arranged in side by side alternate relationship, vertical heating flues in each heating wall and alternate high- and low-burner nozzles in the bases of the vertical heating flues of each heating wall, the high-burner nozzles, except those in the group of vertical flues on the coke side of the battery, being of substantially the same height and having a height within the range of from 2." to 2.75" per foot of heating flue length and the high-burner nozzles in the said group of flues at the coke side of the battery decreasing in height in a direction toward the coke side of the battery, the decrease in height from one high-burner nozzle to the next being within the range of from 15% to 50%, the height of the highest high-burner nozzle in

5 said group of flues at the coke side of the battery being within the range of from 2." to 2.75" per foot of heating flue length, the low-burner nozzles being of substantially the same height and having a height not exceeding .5" per foot of heating flue length.

3. In a coke oven battery having heating walls and coking chambers arranged in side by side alternate relationship, vertical heating flues in each heating wall and alternate high- and low-burner nozzles in the bases of the vertical heating flues of each heating wall, the high-burner nozzles, except those in the group of vertical flues on the coke side of the battery, being of substantially the same height and having a height within the range of from 2." to 2.75" per foot of heating flue length and the high-burner nozzles in the group of flues at the coke side of the battery decreasing in height in a direction toward the coke side of the battery from a maximum height within the range of from 2." to 2.75" per foot of heating flue length to a minimum height within the range of from 1.2" to 1.8" per foot of heating flue length, the decrease in height from one high-burner nozzle to the next being within the range of from 15% to 50%.

4. A coke oven battery having a series of alternate horizontal coking chambers and heating walls therefor arranged in side by side relation, each heating wall comprising two exterior and two interior groups of vertical flues, horizontal channels connecting the tops of the exterior groups, respectively, with the tops of the adjacent interior groups, the two exterior groups being simultaneously operable for flow in one direction and the two interior groups being simultaneously operable for flow in the opposite direction, alternate low- and high-burner nozzles in the base of the heating flues of each heating wall, the high-burner nozzles in all of said groups of flues, except the group of flues on the coke side of the battery, being of substantially the same height and having a height within the range of from 2." to 2.75" per foot of heating flue length, the high-burner nozzles in the group of flues on the coke side of the battery decreasing in height in a direction toward the coke side of the battery from a maximum height within the range of from 2." to 2.75" per foot of heating flue length to a minimum height within the range of from 1.2" to 1.8" per foot of heating flue length.

5. A coke oven battery having a series of alternate horizontal coking chambers and heating walls therefor arranged in side by side relationship, each heating wall comprising two exterior and two interior groups of vertical flues, horizontal channels connecting the tops of the exterior groups, respectively with the tops of the adjacent interior groups, the two exterior groups being simultaneously operable for flow in one direction and the two interior groups being simultaneously operable for flow in the opposite direction, the base of the heating flues being all at the same level and on the same level as the base of the coking chamber, alternate low- and high-burner nozzles in the base of the heating flues of each heating wall, the high-burner nozzles in all of said groups of flues, except the group of flues on the coke side of the battery, being of substantially the same height and having a height within the range of from 2." to 2.75" per foot of heating flue length, the high-burner nozzles in the group of flues on the coke side of the battery decreasing in height in a direction toward the coke side of the battery, the highest burner nozzle in said

group of flues having a height within the range of from 2." to 2.75" per foot of flue length, the next highest a height within the range of from 1.6" to 2.2" per foot of flue length and the lowest a height of from 1.2" to 1.8" per foot of flue length, the decrease in height from one high-burner nozzle to the next being within the range of from 15% to 50% and the low-burner nozzles being of substantially the same height and having a height within the range of from .35" to .5" per foot of flue length.
